CLAIM

The ornamental design for a handle of a toy bubble wand, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a handle of a toy bubble wand;

FIG. 2 is a back view thereof;

FIG. 3 is a side view thereof;

FIG. 4 is a side view thereof;

FIG. 5 is a top view thereof;

FIG. 6 is a bottom view thereof;

FIG. 7 is a front side, perspective view thereof; and,

FIG. 8 is a back side, perspective view thereof.

The part of the photograph shown in a white mask, along with the broken-line perimeter illustrates portions of the handle of a toy bubble wand that forms no part of the claimed design.

1 Claim, 8 Drawing Sheets
